(57) **CLAIM**

The ornamental design for an extendable wash brush, as shown and described.

DESCRIPTION

FIG. 1 is a perspective view of the wash brush;

FIG. 2 is a top plan view thereof;

FIG. 3 is a side elevational view thereof;

FIG. 4 is a front end elevational view thereof;

FIG. 5 is a rear end elevational view thereof; and,

FIG. 6 is a bottom plan view thereof.

The portions shown in broken lines are for illustrative purposes and form no part of the claimed design.
